CLIP FOR AN ELECTRIC LIGHT BULB SOCKET

Maxwell H. Conman, 53 Roosevelt Drive,
Glen Head, N.Y.

Filed Dec. 23, 1964, Ser. No. 83,138

Term of patent 14 years

(Cl. D17—3)

FIG. 1 is a side elevational view of a clip for an electric light bulb socket, embodying my new design;

FIG. 2 is another side elevational view with an electric light bulb socket being shown in broken lines for illustrative purposes only;

FIG. 3 is a perspective view;

FIG. 4 is an end elevational view looking from the left of FIG. 1;

FIG. 5 is an end elevational view looking from the right of FIG. 1; and

FIG. 6 is a bottom plan view thereof.

I claim:

The ornamental design for a clip for an electric light bulb socket, as shown and described.
